UNITED STATES PATENT OFFICE.

ALBERT WESLEY OSTERHOUT, OF BETHANY, NEBRASKA.

TEMPORARY-LEAF HOLDER FOR BOOKS.

1,217,625.

Specification of Letters Patent. Patented Feb. 27, 1917.

Application filed June 20, 1916. Serial No. 104,745.

To all whom it may concern:

Be it known that I, ALBERT WESLEY OSTERHOUT, a citizen of the United States, residing at Bethany, in the county of Lancaster and State of Nebraska, have invented 5 certain new and useful Improvements in Temporary-Leaf Holders for Books, of which the following is a specification.

The present invention relates to means 10 for temporarily securing additional leaves in a book having permanent leaves, and the object is to provide a simple but entirely effective structure whereby additional leaves can be temporarily secured in place in any 15 part of a book desired, thus making it particularly useful for additional notes and the like.

A further object is to provide means that 20 will not materially alter the character of the book nor interfere with its general use.

An embodiment of the invention that has been found entirely satisfactory is illustrated in the accompanying drawings, wherein,

25 Figure 1 is a perspective view of a portion of a book, showing the improvements in place therein.

Fig. 2 is a vertical sectional view through the same on an enlarged scale.

30 Fig. 3 is a detail perspective view of one of the pocket elements, and

Fig. 4 is a detail view of one of the temporary leaf-retaining devices.

Similar reference numerals designate cor- 35 responding parts in all the figures of the drawings.

In the embodiment disclosed, the book is of the usual and well known construction, comprising covers 5 connected by a back 6 40 and having permanent leaves 7 bound therein, the binding of the leaves leaving, as is ordinarily the case, a space 8 between it and the back 6.

In the ends of this space are permanently 45 located pocket elements 9, which may be of leather, chamois or some soft material that will wear well and will also have a certain frictional action upon the devices placed therein, as hereinafter explained. These ele- 50 ments are divided by lines of stitching 10 into a plurality of sockets 11 having their outer ends or mouths open. Each element, as shown, may be formed from a single piece of material doubled upon itself, and the end

margins of the material may be left loose, 55 as indicated at 12 to provide flaps that will overlap the edges of the leaves and constitute guards. These flaps, however, are not absolutely essential to the invention, though 60 advantageous.

The temporary leaf holders are in the form of elastic cords 13 having terminal tips or tongues 14 of some stiff material, such as metal.

In using the device, the temporary leaves 65 15, which may be in the form of folded sheets, are placed at the desired point in the book, one of the straps or cords 13 is located in the fold, and the tips 14 are then inserted in the adjacent sockets 11, as illustrated in Figs. 1 and 2. It will thus be seen that the additional or temporary sheets or 70 leaves will be effectively held in place and may be removed or replaced as desired. The structure and make-up of the book is not 75 materially altered and the additional pocket elements are inexpensive and may either be bound in the book when the same is manufactured or can be afterward inserted and secured in place.

80 From the foregoing, it is thought that the construction, operation and many advantages of the herein described invention will be apparent to those skilled in the art, and it will be understood that various changes 85 in the size, shape, proportion and minor details of construction, may be resorted to without departing from the spirit or scope of the invention.

What I claim as new, and desire to secure 90 by Letters Patent, is:—

1. A book including a cover having a back and permanent leaves bound within the cover and having the binding spaced from the back, in combination with temporary 95 leaf holding means, and means permanently located in the space between the cover back and leaf binding to secure said leaf holding means in place.

2. A book including a cover having a back 100 and permanent leaves bound within the cover, leaving a space between the cover back and binding, a socket member permanently located in the space between the cover back and said leaf binding, and temporary leaf 105 holding devices having portions that detachably engage in the socket member.

3. A book comprising covers, a back and

permanent leaves bound therein, in combination with pocket elements located in the ends of the book between the back and leaf binding and comprising flexible doubled strips having their free ends outwardly extended, said pocket elements having sockets provided with open mouths and temporary leaf holding devices comprising elastic

straps having terminal tongues that detachably engage in the sockets.

In testimony whereof I affix my signature in the presence of two witnesses.

ALBERT WESLEY OSTERHOUT.
